UNITED STATES PATENT OFFICE

JOHAN BULL, OF FOREST HILLS, NEW YORK, ASSIGNOR TO SAKS & COMPANY, OF NEW YORK, N. Y., A CORPORATION OF NEW YORK

DESIGN FOR A PACK OF PLAYING CARDS

Application filed May 28, 1931. Serial No. 40,021. Term of patent 14 years.

To all whom it may concern:

Be it known that I, JOHAN BULL, a citizen of the United States, residing at 44 Slocum Crescent, Forest Hills, State of New York, have invented a new, original, and ornamental Design for a Pack of Playing Cards, of which the following is a specification, reference being had to the accompanying drawings, forming part thereof.

In said drawings:

Design of the face cards, consisting of: Jack of Clubs, Jack of Spades, Jack of Hearts, Jack of Diamonds, Queen of Clubs Queen of Spades, Queen of Hearts, Queen of Diamonds, King of Clubs, King of Spades, King of Hearts, King of Diamonds Joker.

Design of "Spot" card, the border and shaded interior being common to all.

Design of back, common to all.

I claim:

The ornamental design for a pack of playing cards, as shown and described.

JOHAN BULL.
